UNITED STATES PATENT OFFICE.

JOHN P. BURNETT, OF OAK PARK, ILLINOIS, ASSIGNOR, BY DIRECT AND MESNE ASSIGNMENTS, TO AD PHOTOSCOPE COMPANY, INC., OF CHICAGO, ILLINOIS, A CORPORATION OF DELAWARE.

MOTION-PICTURE-FILM MAGAZINE.

1,296,476.

Specification of Letters Patent.

Patented Mar. 4, 1919.

Application filed October 9, 1917. Serial No. 195,632.

To all whom it may concern:

Be it known that I, JOHN P. BURNETT, a citizen of the United States, and a resident of the city of Oak Park, county of 5 Cook, and State of Illinois, have invented certain new and useful Improvements in Motion-Picture-Film Magazines, of which the following is a specification.

My invention relates to improvements in 10 motion picture film magazines, and has for its object the production of a device of this character, designed for use especially in connection with an endless film.

A further object is the production of a 15 magazine as mentioned, in which the film will be so handled in the magazine that cracking or tearing of the film in the withdrawal of the same from the magazine will be positively precluded.

20 A further object is the production of a film magazine, as mentioned, which will be of durable and economical construction and efficient in use.

The invention consists in the combinations and arrangements of parts hereinafter described and claimed.

The invention will be best understood by reference to the accompanying drawings forming a part of this specification, and in 25 which,

Figure 1 is a front elevation of a film magazine embodying the invention, a portion of the door at the front side of the magazine being broken away and a film 30 deflecting member carried thereby being shown in section,

Fig. 2, a vertical transverse section of the device, and

Fig. 3, a top plan view of the device.

40 The preferred form of construction as illustrated in the drawings comprises a circular housing 4 of an interior width equal substantially to or slightly greater than the width of the film A to be used in 45 connection therewith. Said housing is vertically disposed, being secured by means of suitable fastening devices 5 and 6 to a suitable support 7.

The rearward side of housing 4 is open. 50 Snugly fitting in said rearward open side of the housing is a disk 8 which is mounted for free rotary movement about an axis 9 which is carried by the supporting member

7. In order to alleviate friction, rollers or other suitable bearing devices 9' are preferably employed in connection with disk 8. Secured to the front side of disk 8 is a plurality of spaced radially extending curved vanes or blades 10 adapted, when the magazine is in use, to engage with the film introduced into the magazine and effect shifting thereof in the magazine, as will be hereinafter more fully pointed out.

Provided at the upper side of the housing 4 is a film entrance and exit opening 11. 65 The front side of housing 4 is provided with a door 12 secured thereto by hinges 13, a suitable lock 14 being provided to hold the door in closed position.

At one side of the opening 11 are provided 70 suitable film guiding rollers 15, between which the film A is adapted to pass immediately before entering the magazine. Arranged directly below said rollers 15 is a wing or blade 16 adapted to direct the 75 film entering the magazine to the right of the axis of rotation of disk 8. To assist in thus directing the film, the door 12 of the magazine housing is provided at its inner side with a blade 17 which, when the door 80 is closed, forms a continuation of the member 16.

With the construction set forth it will be seen that as the film enters the magazine it will of its own accord fold itself in position 85 at the right hand side of the magazine, resting partially upon the blades 10, the outer portions of the folds or convolutions of the film being adapted to rest against the inner side of the peripheral wall of the housing. 90 The film will be carried around in the magazine and guided out through the opening 11 over a suitable roller 18, as clearly seen in Fig. 1. As the film is fed into the magazine at the right hand side thereof, the weight of 95 the film upon the blades 10 at that side of the magazine will gradually increase and when the weight at that side of the axis of the member 8 reaches a certain point, the weight of the film will automatically, through gravity, cause rotative shifting of the disk 8. In this rotative shifting of the disk 8, the blades 10 at the left hand side of the axis of rotation of said disk, will cause the portions or convolutions of film engaged thereby, to be 100 carried upwardly toward the upper side of

the magazine. This being so it will be seen that the film in being withdrawn from the magazine will always be removed from the outer side or top of the pile of convolutions or folds of film, at the left hand side of the magazine. This being so, no resistance whatever will be offered to the unfolding film in being withdrawn, since there will be no weight whatever upon the uppermost convolution which is always the one which is being unfolded and withdrawn. The film being constantly fed into the magazine, at the right hand side thereof, the weight upon the blades 10 or upon the disk 8 will always be increasing at the right hand side of the axis of the disk, and the film being always withdrawn from the left hand side of the magazine will result in the weight upon the blades 10 to the left of the axis of rotation, being constantly diminished, the result being that the disk 8 will gradually and constantly rotate by gravity, causing rotative shifting of the disk in the magazine, as just described. By curving the blades 10, as shown, that is so that the convex sides thereof will be uppermost at the right hand side of the magazine and the concave sides thereof will be uppermost at the left hand side of the magazine, said blades will tend to shift the convolutions of film at the right hand or entry side of the machine outwardly toward the periphery of the magazine, and will tend to a certain extent to shift the convolutions toward the center of the magazine at the other or discharge side thereof. This will of course tend to increase the leverage of the film convolutions at the entry side of the magazine and decrease the leverage of the film convolutions at the other side of the magazine, thereby aiding in effecting the desired rotative shifting of the disk 8 in a clockwise direction.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A motion picture film magazine comprising a housing adapted to receive the film; a film shifting element mounted in said housing for rotation about a horizontal axis; and film engaging means on said element, substantially as described.

2. A motion picture film magazine comprising a housing adapted to receive the film; a film shifting element mounted in said housing for rotation about a horizontal

axis; and substantially radially disposed film engaging means on said element, substantially as described.

3. A motion picture film magazine comprising a housing adapted to receive the film; a film shifting element mounted in said housing for rotation about a horizontal axis; and substantially radially disposed vanes on said element for engagement with the film introduced into said housing, substantially as described.

4. A motion picture film magazine comprising a housing adapted to receive the film; a film shifting element mounted in said housing for rotation about a horizontal axis; and substantially radially disposed curved vanes on said element for engagement with the film introduced into said housing, substantially as described.

5. A motion picture film magazine comprising a housing adapted to receive the film; a film shifting element arranged in said housing comprising a vertically disposed disk mounted for free rotation about a horizontal axis; and film engaging means carried by said disk, substantially as described.

6. A motion picture film magazine comprising a housing adapted to receive the film; a film shifting element arranged in said housing comprising a vertically disposed disk mounted for free rotation about a horizontal axis; and vanes carried by said disk for engagement with the film introduced into said housing, substantially as described.

7. A motion picture film magazine comprising a comparatively narrow circular housing adapted to receive the film; a film shifting element arranged in said housing comprising a vertically disposed disk mounted for free rotation about a horizontal axis; and film engaging means carried by said disk, substantially as described.

8. A motion picture film magazine comprising a comparatively narrow circular housing adapted to receive the film; a film shifting element arranged in said housing comprising a vertically disposed disk mounted for free rotation about a horizontal axis; film engaging means carried by said disk; and a door at one side of said housing, substantially as described.

9. A motion picture film magazine comprising a housing adapted to receive the film; a film shifting element mounted in said housing for rotation about a horizontal axis; film engaging means on said element; and means for directing the film entering said housing to one side of the axis of said film shifting element, substantially as described.

10. A motion picture film magazine comprising a housing adapted to receive the film; a film shifting element mounted in said

housing for rotation about a horizontal axis; film engaging means on said element; and an entrance and exit opening for the film at the upper side of said housing, substantially as described.

11. A motion picture film magazine comprising a housing into which the film is adapted to be guided and folded; and means for simultaneously bodily shifting all of the 10 folds of film in said housing, substantially as described.

12. A motion picture film magazine comprising a housing into which the film is adapted to be guided and folded; and 15 gravity-controlled means for simultaneously bodily shifting all of the folds of film in said housing, substantially as described.

13. A motion picture film magazine comprising a housing into which the film is 20 adapted to be guided and folded and from which the film is adapted to be withdrawn; and means for bodily shifting the folds of film in said housing so that each fold of the film, as the same is unfolded in the withdrawal of the film from the magazine, will 25 be uppermost, substantially as described.

14. A motion picture film magazine comprising a housing into which the film is adapted to be guided and folded and from 30 which the film is adapted to be withdrawn; and means for bodily rotatively shifting the folds of film in said housing so that each fold of the film, as the same is unfolded in

the withdrawal of the film from the magazine, will be uppermost, substantially as 35 described.

15. A motion picture film magazine comprising a housing into which the film is adapted to be guided and folded and from 40 which the film is adapted to be withdrawn; and means operable by the weight of the film introduced in said housing for bodily shifting the folds of film in said housing so that each fold of the film, as the same is unfolded in the withdrawal of the film from 45 the magazine, will be uppermost, substantially as described.

16. A motion picture film magazine comprising a housing into which the film is adapted to be guided and folded and from 50 which the film is adapted to be withdrawn; and means operable by the weight of the film introduced in said housing for bodily rotatively shifting the folds of film in said 55 housing so that each fold of the film, as the same is unfolded in the withdrawal of the film from the magazine, will be uppermost, substantially as described.

In testimony whereof I have signed my name to this specification in the presence of 60 two subscribing witnesses.

JOHN P. BURNETT.
